UNITED STATES PATENT OFFICE.

JOSEPH SOSS, OF BROOKLYN, NEW YORK.

CASKET HINGE.

Application filed April 21, 1926. Serial No. 103,501.

This invention relates to hinges and particularly devices of this class for use in connection with caskets for movably supporting the cover or closures thereof with the main body or case portion of the casket; and the object of the invention is to provide a hinge of simple and economical construction and yet one of strength and durability whereby the cover or closure member of articles of the class specified or similar articles, may be hingedly supported; a further object being to provide a hinge of the class specified whereby the desired swing or throw of the cover or closure is provided and further whereby the desired result may be accomplished in a hinge which will take up the least amount of space, or project beyond the inner faces of the wall of the case or cover to the slightest degree possible; and with these and other objects in view, the invention consists in a hinge of the class and for the purpose specified which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a perspective view of a part of the inside of a casket and part of a cover therefor, with the cover in a partially open position, and with part of the construction broken away.

Fig. 2 is a transverse section of the construction shown in Fig. 1 with the cover in a closed position.

Fig. 3 is a view similar to Fig. 2 but showing the cover in a fully open position.

Fig. 4 is a plan view of the construction as seen in Fig. 3.

Fig. 5 is a partial section on the line 5—5 of Fig. 3; and,

Fig. 6 is a view similar to Fig. 5 but showing a modification.

In the drawing, 10 represents a part of one side wall of a burial casket and 11, a part of a cover therefor, said cover being continuous for the entire casket structure or a partial cover such as commonly employed at the head end portion of the casket. In Fig. 1 of the drawing, I have indicated at 12 the lining or facing material commonly employed on the inner face of the casket 10 and cover 11, and which encloses my improved hinge

construction for hingedly supporting the cover 11 in connection with the casket 10.

In practice, one side wall of the casket 10 is provided with one or more V-shaped recesses or apertures 15 only one being shown for the purpose of illustration. Said aperture opens through the inner face of the side wall and through the top edge thereof as clearly seen in Figs. 2 and 3 of the drawing. The cover 11 is provided with a similar recess or aperture 16 in alinement with the recess or aperture 15.

My improved hinge consists of two substantially similar butt members 13 and 14 which in the construction shown, are fashioned from sheet metal. The butt member 13 is secured to the casket 10 and the butt member 14 secured to the cover 11 as seen.

In the construction shown, the butt member 13 is fashioned from sheet metal to form a substantially V-shaped channel portion 13^a, the side walls of the channel preferably projecting beyond the inner face of the casket 10 and are provided with elongated apertures 13^b. The lower or contracted end of the channel 13^a is provided with a projecting tongue 13^c apertured to receive a screw 17 for securing said end of the butt 13 to the casket 10, while the upper or enlarged end of the butt 13 has laterally directed ears or flanges 13^d having apertures to receive attaching screws 18 which pass into the casket 10.

The butt member 14 is formed similar to the butt member 13 and consists of a substantially V-shaped channel portion 14^a, the side walls of the channel preferably projecting beyond the inner edge of the cover 11 and are provided with elongated apertures 14^b. The contracted end of the channel 14^a is provided with a projecting tongue 14^c apertured to receive a screw 19 for securing said end of the butt 14 to the cover 11, while the enlarged end of the butt 14 has laterally directed ears or flanges 14^d having apertures to receive attaching screws 20 which pass into the cover 11.

In practice, the separate butts 13 and 14 are coupled together by hinge links 21 and 22, two of which are shown in the accompanying drawing, but any number of which may be employed in duplicate, in the manner of other hinges of this class to give the required strength and durability to the hinge, said hinge links being of the general form clearly seen in Figs. 2 and 3 of the drawing

and being pivotally coupled together as seen at 23. The link 21 is pivoted to the hinge butt 13 as shown at 24 while the link 22 is pivoted to the hinge butt 14 as seen at 25.
5 The free end of the link 21 is provided with a pin 26 which projects laterally and operates in the elongated aperture 14^b of the butt 14, note Figs. 1 and 5 of the drawing, while the free end of the link 22 is provided with 10 a pin 27 and the ends of which project and operate in elongated apertures 13^b of the hinge butt 13.

It will be noted that the shape or form of the links 21 and 22 and manner of their 15 pivotal connection with each other and with the separate butts is such as to maintain said links as close as possible to the inner faces of the casket 10 and cover 11 and yet permit of the opening of the cover 11 into 20 such position as to bring the lower face 11^a in horizontal alinement with the upper face 10^a of the casket 10 as seen in Fig. 3 of the drawing and also to bring said faces closely together as seen in Fig. 2 of the drawing.
25 It will also be apparent that the cover 11 may be supported in a partially open position as seen in Fig. 1 of the drawing for display or other purposes; and as previously stated, it will be apparent that any number 30 of hinges may be employed for hingedly supporting the cover 11 in connection with the casket 10, and the size and dimensions of the butts and link members and the number of link members employed may be varied 35 to suit the requirements.

In Fig. 6 of the drawing, I have shown a slight modification in which I have substituted for the elongated apertures 13^b and 14^b in the hinge butts 13 and 14, channels or depressions, in which the pins 26 and 27 are adapted to operate. For illustrative purposes, I have shown in Fig. 6 of the drawing, the hinge butt 14 provided with channels 14^c instead of the apertures 14^b in which the pin 26 of the link 21 operates, it being understood that the hinge butt 14 may be similarly formed. The structure shown in Fig. 6 of the drawing will give greater strength to that part of the butts in connection with which the pins 26 and 27 operate.

It will be understood that I am not necessarily limited to the specific manner of movably coupling the links 21 and 22 with the 55 respective butts nor am I necessarily limited to the specific form and construction of the separate butts nor to the specific use of the hinge herein shown and described, and various other changes in and modifications of 60 the construction herein set out may be made within the scope of the appended claims without departing from the spirit of my invention or sacrificing its advantages.

It will be apparent that one of the dis- 65 tinctive features of my invention resides in

the angular arrangement of the hinge butts with reference to each other when the butts are in closed position; that is to say, when the hinge cover member assumes its closed position which is contrary to hinges of general construction and further in the fact that the hinge cover member 11 is capable of movement through an arc of 180 degrees above the link construction employed, and this feature in an invisible hinge is distinctively characteristic.

Having fully described my invention, what I claim as new and desire to secure by Letters Patent, is:—

1. A hinge comprising two butt members 80 fashioned from sheet metal and comprising elongated channel bodies V-shaped in longitudinal plan, the side walls of said bodies being arranged in parallel relation and having elongated apertures extending longitudinally thereof, hinged links pivoted to and mounted within enlarged end portions of said butts, the free end portions of said links being mounted and adapted to operate in the elongated apertures in the side walls of 90 opposed butts, said butts being mounted on a stationary support and swinging member with the enlarged ends adjacent when the swinging member is in a closed position, and the contracted ends of the butts being extended in angular relation with reference to each other.

2. A hinge comprising two butt members 100 fashioned from sheet metal and comprising elongated channel bodies V-shaped in longitudinal plan, the side walls of said bodies being arranged in parallel relation and having elongated apertures extending longitudinally thereof, hinged links pivoted to and mounted within enlarged end portions 105 of said butts, the free end portions of said links being mounted and adapted to operate in the elongated apertures in the side walls of opposed butts, said butts being mounted on a stationary support and swinging member with the enlarged ends adjacent when the swinging member is in a closed position, the contracted ends of the butts being extended in angular relation with reference to 110 each other, and said links being pivoted together in such manner as to permit the movement of the swinging member through an arc of one hundred and eighty degrees.

3. A hinge comprising two butt members 120 fashioned from sheet metal and comprising elongated channel bodies V-shaped in longitudinal plan, the side walls of said bodies being arranged in parallel relation and having elongated apertures extending longitudinally thereof, hinged links pivoted 125 to and mounted within enlarged end portions of said butts, the free end portions of said links being mounted and adapted to operate in elongated apertures in the side walls of opposed butts, said butts being 130

mounted on a stationary support and swing-
ing member with the enlarged ends adjacent
when the swinging member is in a closed
position, the contracted ends of the butts
5 being extended in angular relation with
reference to each other, said links being
pivoted together in such manner as to per-
mit the movement of the swinging member

through an arc of one hundred and eighty
degrees, and means at the contracted and 10
enlarged end portions of the butts for se-
curing the same in their respective supports.

In testimony that I claim the foregoing as
my invention I have signed my name this
14th day of April, 1926.

JOSEPH SOSS.
